UNITED STATES PATENT OFFICE.

WILLIAM COURTNEY McKINNEY, OF NEW BRIGHTON, PENNSYLVANIA,
ASSIGNOR TO STANDARD SANITARY MFG. CO., OF PITTSBURG, PENN-
SYLVANIA, A CORPORATION OF NEW JERSEY.

DREDGING IMPLEMENT.

No. 851,605.

Specification of Letters Patent. Patented April 23, 1907.

Application filed March 26, 1906. Serial No. 308,148.

To all whom it may concern:

Be it known that I, WILLIAM COURTNEY McKINNEY, a citizen of the United States, residing at New Brighton, in the county of Beaver and State of Pennsylvania, have invented a new and useful Dredging Implement, of which the following is a specification.

My invention relates to sifting implements employed in enameling and similar work, and is termed in the art "dredges."

A principal object of the invention is to provide an implement of the character described which has means for carrying a considerable amount of enamel or coating material, usually sufficient for several pieces of work, in connection with a suitable device for applying the enamel or the like to the work.

The characteristics and advantages of my invention are hereinafter more fully set forth in connection with the accompanying drawing which illustrates an exemplifying structure in which the invention is embodied.

Figure 1 is a view of a dredge embodying my invention; and Fig. 2, a partial plan view of Fig. 1, showing the magazine or box with its cover removed.

1 is a tube of any suitable proportions, the length depending upon the character of the work in which it is to be employed; 2, a sieve placed at one end of the tube and conveniently formed of woven wire fabric of proper sized mesh, although other material may be employed.

The invention may be said to consist of a dredge for applying pulverized coating to normally inaccessible locations, comprising a relatively small-necked tube 1 capped by 40 a sieve 2 at its delivery end and constituting a magazine or an auxiliary thereto.

In a great variety of enameled work, such as enameled iron work, difficulty has been experienced in applying the enamel to certain parts of the articles, such, for instance, as the overflows of lavatories and similar locations which are difficult of access.

The invention, in one of its simplest forms, may consist of the two parts above described.

50 The tube 1 is filled with the enamel or coat-

ing material, and because of its length may hold a sufficient quantity of the material to enamel several pieces of work.

In operation the sieve 2 is inserted into the part which it is desired to enamel, and the tube is vibrated by hammering with an implement, such as a rod, held by the workman. This shakes the sieve, and the coating is deposited upon the work in the desired manner. Instead of the hand device the tube may, in some cases, be vibrated by mechanical means, but the exact method of vibrating the tube is not essential.

In some cases it is desired to provide a magazine of greater capacity than is afforded by the interior of the tube, in order to allow the implement to be used for a larger number of pieces of work, without stopping to refill. In such cases a magazine, such as the box 3, may be secured to the tube in any suitable manner. A passage 4 is provided leading from the box to the tube and the box may be filled with coating material, and when the implement is in operation this material will pass from the box into the tube and out through the sieve in an obvious manner.

The invention, I believe, is broadly new with me, and I do not limit myself to the details shown and described. Many variations may be made therein without departing from the spirit of the invention. Among other changes, instead of using the sieve as shown, the end of the tube may be suitably closed and provided with perforations through which the coating material may be shaken, securing practically the same result as by the use of the sieve.

What I claim is:

A dredge for applying pulverized coating, adapted to be inserted into normally inaccessible locations, comprising a relatively small-necked tube capped by a sieve at one end, and a magazine connected therewith.

In testimony whereof I have affixed my signature in the presence of two witnesses:

95

WILLIAM COURTNEY McKINNEY.
